UNITED STATES PATENT OFFICE.

ALLAN L. McGREGOR, OF CHICAGO, ILLINOIS.

PRESS.

1,182,023.

Specification of Letters Patent.

Patented May 9, 1913.

Application filed March 9, 1916. Serial No. 82,023.

To all whom it may concern:

Be it known that I, ALLAN L. McGREGOR, a citizen of the United States, and a resident of Chicago, in the county of Cook and State 5 of Illinois, have invented certain new and useful Improvements in Presses, of which the following is a specification.

My invention relates to presses particularly adaptable for use in garages in the re- 10 pair of motor vehicles.

The object of the invention is to produce a press of simple and inexpensive construction yet one which possesses great strength and whose capacity is very large as com- 15 pared to its own weight.

The object is further to provide such arrangement that the press can be adapted for a variety of work and can be very readily operated by hand with little exertion to get 20 very great pressure.

On the accompanying drawings I have shown a press embodying the features of my invention.

On these drawings Figure 1 is a side elevational view, Fig. 2 is a front elevational view, Fig. 3 is an enlarged sectional view on plane 3—3, Fig. 2, Fig. 4 is an under side view of a base plate adapted to be applied to the press for supporting work, Fig. 5 is a sectional view on plane 5—5, Fig. 4, and Fig. 6 is an enlarged elevational view showing pipe jaw mechanism adapted for coöperation with the press to support pipes, shafts or the like.

The press frame comprises side standards 10 and 11 preferably in the form of channel beams, the transverse beams 12 and 13 at the bottom of the sides to form supporting base, and the arched top 14 secured at its ends to 35 the tops of the sides. Near the top the sides 10 and 11 are secured together by the transverse front and rear channel beams 15 and 16, and at the lower ends the sides are secured by front and rear beams 17 and 18 40 which, as shown, are in the form of angle bars. The various parts of the frame may be riveted, bolted, or otherwise rigidly secured together to form a strong and rigid structure. The front and rear flanges of the 45 side beams 10 and 11 have the bolt holes 19 and 20 respectively by means of which front and rear plates 21 and 22 may be secured at any level desired by means of the bolts 23 and 24, these plates forming a sup- 50 port for work to be operated on by the press.

Extending centrally of the press and between the beams 15 and 16 is the guide frame 25 for the press screw 26, bolts 27 rigidly securing the frame to the beams. The frame is further held in place by a bolt 28 extending downwardly from the arched top 14 of the press frame, a spacer 29 surrounding the bolt between the arch and the top of the frame 25. At its lower end the frame 25 has the cross head 30 from which extends 60 the stirrup 31. The cross head 30 has the opening 32 and the stirrup has the opening 33, through which openings the screw 26 is free to shift longitudinally, the screw being prevented from turning by a pin 34 extending transversely through the upper end thereof and into the opposite slots 35 and 36 in the frame 25. Surrounding and threaded to receive the screw is the hub 37 which extends between the cross head 30 and the bottom of stirrup 31 and this hub carries a large bevel gear 38. With this gear meshes the pinion 39 which is secured to the inner end of the transverse shaft 40 journaled in the hangers 41 secured to the beams 15 and 16, 70 the shaft extending through the side beam 10 and terminating in a hand wheel 42 which may be provided with radial hand grips 43. When this wheel is turned to rotate the shaft 40 and pinion 39 the large gear 38 will be 75 rotated and the screw 26 will be raised and lowered, the gearing ratio and screw pitch being such that the screw will exert very heavy pressure. The hand wheel 42 suffices 80 for ordinary work, but if extra heavy pressure is desired the long lever 44 is operated, this lever being applied in the socket frame 45 rotatable at its lower end on the shaft 40 adjacent to a pawl wheel 46 secured to the shaft, a pawl 47 being pivoted to the socket frame 45 to coöperate with the pawl wheel in the well known manner. Any length of lever can be applied in the socket frame 45. 85 At its lower end the screw 26 has a socket 48 into which tools or other appliances may be secured. In Fig. 2 the press is being utilized to remove a shaft *a* from a gear *b*. The gear rests on pieces of channel bars *c* and *d* with the shaft extending downwardly between them and the plates 21 and 22, and a tool *e* is secured in the socket 48 by a set screw 49 and bears at its lower end against the top of the shaft *a* to be removed. When the hand wheel 42 or the lever 44 is now 90 turned the tool *e* will exert heavy pressure 95 100 105 110

against the shaft and the shaft can readily be removed from the gear *b* without in any wise mutilating the gear. The plates 21 and 22 can be readily shifted on the press 5 frame from one plane to another depending on the work to be accomplished by the press. It is of course obvious that the device can also be used for exerting heavy pull.

In Fig. 4 I have shown a block shaped to 10 coöperate with the plates 21 and 22 to form a support for work. This block has the downwardly depending peripheral flange 50 provided with parallel transverse slots 51 and 52 for receiving the upper edges of the 15 plates 21 and 22 respectively, such engagement securing the block against rotation. The block may also be provided with one or more openings 53. In Fig. 6 I show upper and lower jaw members 54 and 55, the upper 20 jaw member having the shank 56 by means of which it may be secured in the socket 48 of the screw 26. The lower jaw member has the cylindrical lug 57 which, for example, may fit into the opening 53 of the block 25 shown in Figs. 4 and 5. The jaw members have the V-shaped notches 58 and 59 respectively which may be serrated so that pipes, shafts or similar articles may be securely clamped between the jaw members 30 when the press is operated. Different fittings can of course be provided for the press to accommodate all classes of work.

The press shown is of simple and inexpensive construction, stock material being 35 used entirely for the supporting frame while the other parts may be in the form of inexpensive castings. The press is therefore very light yet has great strength, and owing to the gear and pitch relationship tremendous pressure or pull can be exerted by the 40 screw during application of ordinary force by one man to the hand wheel or lever mechanism. I do not of course desire to be limited to the exact constructions and arrangements shown as modifications are no doubt 45 possible which would still come within the scope of the invention.

I claim as follows:

1. In a press, the combination with a 50 frame comprising side beams, base beams, a top beam extending across and secured to the upper ends of the side beams, and transverse upper beams secured to the side beams, of work supporting plates vertically adjustable on said side beams, a vertical screw frame secured to the cross beams and to the top, a screw vertically shiftable in said screw frame, means for preventing rotation of said screw, a gear within said screw frame and having threaded engagement with said screw, a transverse shaft journaled on the press frame, a pinion on said shaft meshing with said gear, and a hand wheel on said shaft.

2. In a press of the class described, the

combination of a frame structure comprising channel beam sides, transverse beams secured to said side beams adjacent to the top thereof, a vertical screw frame secured to said transverse beams, a screw shiftable longitudinally in said screw frame, gear mechanism controlled from the exterior of the frame structure for shifting said screw, said side beams having vertically spaced bolt holes through their flanges, work supporting plates, and bolts passing through said plates and side beam holes for securing said plates to the side beams at any level to be below said screw to support work to be operated on.

3. In a press of the class described, the combination of a rectangular supporting frame structure comprising side beams and upper transverse beams, a screw frame extending vertically between said upper transverse beams and secured thereto, a screw longitudinally shiftable in said screw frame, pins extending laterally from said screw and said screw frame having vertical slots for receiving said pins to prevent turning of the screw during reciprocation thereof, a gear mounted in said screw frame and having threaded engagement with said screw, a shaft journaled on said press frame structure, a pinion on said shaft meshing with said gear, means for turning said shaft, and an adjustable work support secured to the press frame side beams below said screw.

4. In a press of the class described, the combination of a supporting frame structure 100 comprising vertical side beams and upper transverse beams, a vertical screw frame secured to said transverse beams, a screw shiftable longitudinally within said screw frame, means for preventing the turning of said 105 screw in said frame, a gear supported on said screw frame and having threaded engagement with said screw, a shaft, a pinion on said shaft meshing with said gear, a hand wheel for turning said shaft, a lever structure pivoted on said shaft, a pawl pivoted on said lever structure, a pawl wheel secured to said shaft, and a work support adjustably secured to the press frame side beams below the screw.

5. In a press of the class described, the combination with a supporting frame structure comprising vertical side beams, upper transverse beams connecting said side beams and an arched top bridging said side beams, of a vertical screw frame extending between said transverse beams and secured thereto and secured also to said arched top, a cross head at the lower end of said screw frame and a stirrup extending downwardly 125 from said cross-head, said cross head and stirrup having aligned openings, a screw shiftable longitudinally in said screw frame and through said openings, said screw frame having a slot, a pin extending from said 130

screw into said slot to prevent turning of the screw during reciprocation thereof, a hub between said cross head and stirrup having threaded engagement with said screw, a gear 5 on said hub, a transverse shaft journaled on said press frame structure, a pinion on said shaft meshing with said gear, means for ro-

tating said shaft, and a work support vertically adjustable on said side beams below said screw.

In witness whereof I hereunto set my hand this 7th day of March, A. D., 1916.

ALLAN L. McGREGOR.
